UNITED STATES PATENT OFFICE.

JOSEPH B. PLATT, OF CLEVELAND, OHIO.

DASH-BOARD.

SPECIFICATION forming part of Letters Patent No. 259,651, dated June 13, 1882.

Application filed April 3, 1882. (Model.)

To all whom it may concern:

Be it known that I, JOSEPH B. PLATT, of Cleveland, in the county of Cuyahoga and State of Ohio, have invented new and useful 5 Improvements in Carriage-Dash Feet, of which the following is a specification.

The nature and objects of this improvement will fully appear from the subjoined description, when considered in connection with the 10 accompanying drawings, in which—

Figure 1 is a front elevation. Fig. 2 is a vertical section. Fig. 3 is a detached view of the bolt, rail, and washer.

A is a dash, made of leather, in the lower 15 edge of which is secured the lower rail, B, of the frame, consisting of a curved channel-iron having a square hole, b, for the bolt C.

D is an iron foot for securing the dash to a carriage-body. It has an elbow and arm terminating in a slotted T-head, d, having a curved surface for fitting onto the curved side 20 of the rail B.

E is a washer, also curved to fit over the slotted T-head, and against which the nut e of 25 the bolt C bears.

It will be observed that the head of the bolt C has two beveled sides, so that when the bolt is in place the beveled sides rest against the beveled sides of the flanges of the rail B, leaving the flat surface of the bolt-head flush with the edges of the said flanges. The object of 30 making the bolt-head beveled, as shown, is so that the bolt may be inserted in the hole in the rail, head first, after the dashes have been 35 finished, and leave the leather on the outside of the rail uncut. The object of making the T-head of the foot-piece slotted is to enable the foot to be adjusted to the body when at-

taching the dash thereto. The object of thus constructing these dash-feet is that they may 40 be supplied to the trade as a separate article of commerce.

The dashes are made with the lower rail having the hole, and when the carriage-builder desires to attach them to a carriage he cuts 45 the leather on the inside of the dash over the hole sufficient to insert the bolt. The bolt is inserted by first removing it from the other parts, and then putting one of the bevel-edges of the head into the hole first, then turning 50 the shank of the bolt outward at right angle from the dash, which movement enters the opposite bevel-edge of the head. Then the bolt is given a quarter-turn, which brings the bevel-sides against the bevel-sides of the flanges, as 55 seen in Fig. 2.

The foot D is secured to the body of the carriage in its proper place with screws. Then the dash may be secured by inserting the bolt in the slot of the head, placing on the washer, 60 and screwing on the nut.

By this improvement in the construction dashes and bodies of varying widths may be readily adjusted in attaching them.

Having described my invention, I claim— 65

The combination, with the dash A, having the curved channel-rail B, of the bevel-headed bolt C, slotted T-headed foot-piece D, curved washer E, and nut e, constructed and arranged for adjustment substantially as and for the 70 purpose specified.

JOSEPH B. PLATT.
